ALDEN L. McMURTRY, OF SOUND BEACH, CONNECTICUT.

BUBBLE-HAT.

1,021,323.

Specification of Letters Patent. Patented Mar. 26, 1912.

Application filed May 6, 1911. Serial No. 625,444.

To all whom it may concern:

Be it known that I, ALDEN L. McMURTRY, a citizen of the United States, and a resident of Sound Beach, in Fairfield county, and State of Connecticut, United States of America, have invented certain new and useful Improvements in Bubble-Hats, of which the following is a specification.

10 My invention relates to a device which may be called a bubble hat, which is an arrangement combined with a hat for producing soap bubbles therefrom. Its object is to provide a device of this kind for theatrical or scenic effects.

In the specification I will describe the construction and the novel arrangement of parts which I have invented, and will point out the novel features thereof in the appended claims.

The drawing shows my invention in perspective with a portion thereof drawn in section. The hat is shown on a wearer in order to illustrate how it is to be used.

25 10 designates a cuplike receptacle which is arranged to be attached in some suitable manner to the head of a person. Preferably this receptacle is affixed to the crown of a hat 11 which, for the purpose of more effectively concealing it, may be a trimmed hat as shown. A part of this hat is broken away in the drawing in order to more clearly show the device. A tube 12 projects through the receptacle into the lower

30 central portion thereof. This tube is bent up about one side of the receptacle so that liquid in the receptacle will not run out through it. This tube is carried down as at 13 and is connected with the outlet of a 35 small portable gas tank 14. This outlet is manually controlled by means of a self-closing valve 15. The gas tank is to be carried upon the person of the user of this apparatus and is to be concealed. It is filled 40 with some suitable light gas such as hydrogen under pressure. The cuplike receptacle is to be partly filled with a solution of soap and water.

The wearer of this device may at will open 45 the valve 15 momentarily, thus allowing some of the gas from the tank 14 to escape up through the tubing 13 and out through

the end of the tube 12 which is under the soap and water solution. This will cause a soap bubble to be formed which, on account of the lightness of the gas, will release itself and will ascend. This operation may be repeated at desired intervals, or, by holding the valve open, a plurality of bubbles may be formed in rapid succession. 55 60

This device is designed primarily for theatrical purpose and it is to be understood that a number of persons such as the members of a chorus may be equipped with such apparatus so that they may together or singly cause bubbles to arise from their heads, either in conjunction with a song or otherwise. Thus, a strikingly novel scenic effect is produced which may be largely enhanced by having colored lights projected 70 upon the bubbles.

What I claim is.—

1. A cuplike receptacle, means for attaching said receptacle to a person's body, a tube projecting through the lower portion 75 of the receptacle, a portable gas tank connected with said tube, and a manually controlled valve.

2. A cuplike receptacle, means for attaching said receptacle to a person's head, a tube projecting through the lower portion 80 of the receptacle, said tube extending upward on the outside of the receptacle, a portable gas tank, a manually controlled valve therefor, and a hollow flexible connection between the tank and the tube.

3. A hat, a cuplike receptacle therein, a tube projecting through the lower portion 90 of the receptacle, a gas tank connected with said tube, and a manually controlled valve.

4. A hat, a cuplike receptacle therein, a tube projecting through the lower portion 95 of the receptacle, said tube extending upward on the outside of the receptacle, a portable gas tank, a manually controlled valve therefor, and a hollow flexible connection between the tank and the tube.

In testimony whereof I have signed my name to this specification in the presence of two subscribing witnesses.

ALDEN L. McMURTRY.
